UNITED STATES PATENT OFFICE.

GEORGE HENRY WHEARY, OF RACINE, WISCONSIN.

DESIGN FOR A TRUNK.

46,921.

Specification for Design.

Patented Feb. 2, 1915.

Application filed November 9, 1914. Serial No. 871,217. Term of patent 14 years.

To all whom it may concern:

Be it known that I, GEORGE HENRY WHEARY, a citizen of the United States, residing at Racine, in the county of Racine and State of Wisconsin, have invented a new, original, and ornamental Design for Trunks, of which the following is a description, reference being had to the accompanying drawing, forming part thereof.

The figure is a perspective view of a trunk showing my new design.

I claim:

The ornamental design for a trunk, as shown.

GEORGE HENRY WHEARY.

Witnesses:

ANNA M. NELSON,
AL. A. RITTER.
